SIGN COMPOSING APPARATUS

Quinton Buras, Birmingham, Ala.

Application August 26, 1938, Serial No. 227,013

3 Claims. (Cl. 40—28)

My invention relates generally to means for mechanically composing lettered signs, and particularly to an arrangement of this character which operates automatically to set up the desired lettering or sign upon the successive operation of selective letter releasing means, and an important object of my invention is to provide a simple and efficient arrangement of this character which greatly facilitates the setting up of lettered signs and saves considerable time and expense of producing the same.

Other important objects and advantages of my invention will be apparent from a reading of the following description taken in connection with the drawings, wherein for purposes of illustration I have shown a preferred embodiment of my invention.

In the drawings:

Figure 1 is a general front elevational view of apparatus in accordance with the present invention.

Figure 2 is an enlarged detail of the slug releasing mechanism.

Figure 3 is an enlarged fragmentary elevational view of the slug receiving and disposing mechanism which operates automatically upon the depositing of a slug therein.

Figure 4 is a front elevational view of a sign support.

Figure 5 is a front elevational view of another form of sign support.

Figure 6 is a perspective view of another type of sign support.

Referring in detail to the drawings, the numeral 5 generally designates a magazine holding vertical rows 6 of slugs 7, each row containing a number of slugs of the same letter and the rows being arranged in side by side relation. Below the magazine 5 is the guide casing 6' which mounts the keyboard 8 which is composed of vertically spaced horizontal rows of keys 9 which have the letter 10 thereon corresponding to the particular row of slugs in the magazine 5 which are to be selectively released to fall into the chute 11 which has a tapered lower end portion 12 which terminates in a chute 13.

Referring now to Figure 2 of the drawings, each individual row 6 is duplex in character, involving as it does front and back slotted guides 14 and 15, respectively, and an extra slotted guide 16 opposed to the middle guide 15 to hold extra slugs. The slugs 7 are disposed between the guides 14 and 15 while spare slugs 7' are disposed between the guides 15 and 16. The guides are flat tubes conforming in width to the slugs 7 and 7', and defined by front and back plates 17 and 18, respectively, which are spaced by the respective guides 14, 15 and 16. The guide 14 has a projection 19 above its lower end which is in the nature of a bracket and this has a reduced

shank 20 on which is circumposed an expanding spring 21 which operates between the projection 19 and the upper part of the tiltable arm which is generally designated 22 and through which the shank 20 projects at its upper end. Another projection 23 below the projection 19 has a shank 24 on which is circumposed a spring 25 which operates between the projection 23 and a washer 26 which is slidable on the shank 24 and works against the inner side of the swingable arm 22, a nut 27 being fitted on the outer end of the shank 24 to engage against the outer side of the arm 22. Another projection 28 on the guide 14 and below the projection 23 has a standard 29 thereon which is provided with an adjustable bolt 30 which has a stop head 31 thereon for engagement by the arm 22, and the projection 28 is traversed by a pivot 32 which traverses the side members of the arm 22 which straddle the projection 28, thereby the arm 22 is fulcrumed on the pivot 32 and supported by the projection 28. The side member 33 of the arm 22 projects downwardly and in between the arms of a bifurcation 34 in which position it is pivoted by means of a pivot device 35, and depends below the slidable stop 36 where a cable 37 is attached to the lower end of the side member 33 and is trained over a pulley 38 and connected to the intermediate portion of the downwardly swingable key 9 which is pivoted as indicated by the numeral 39 on the keyboard 8 in some suitable manner, so that whenever the key 9 is depressed the lower end of the arm 22 will be swung toward the left in Figure 2 and slidably withdraw the stop 36 from under the lowermost one of the slugs 7, the stop 36 being mounted in an opening 40 formed in the guide 14, the arm 22 being restored to original position after release of the key 9 by the springs 21 and 25. A hand operated stop 41 is slidably mounted in an opening 42 in the guide 16 and is normally held in closed position by a spring 43 so as to releasably hold the spare slugs 7'.

When the selected slugs 7 are released by operating the keys 9 the slugs fall into the chute 11 and slide and fall to the receiver 13 shown in Figure 3 of the drawings. In conjunction with and at one side of this receiver 13 is placed a frame which is generically designated 45 and which may comprise that form shown in Figure 3 or any of those shown in Figures 4, 5 and 6 essentially comprising upper and lower longitudinally slotted members 46 and 47, the form 45 constituting, when filled up as desired with the proper slugs 7, a part of the sign to be constructed or composed. The lower member 47 is aligned with the lower horizontal member 49 which is spaced below the lower end of the receiver 13 and is provided with ball-bearings 50 facilitating movement of the slugs 7 as dropped from the receiver 13, to a position between the members 60

46 and 47. As the slug 7 comes down through the receiver 13 the same strikes upon the uplifted end of the pivoted contact 51 causing the opposite end of this contact to rise against the resistance of the spring 52 and engage the relatively stationary contact 53, thereby closing an electrical circuit to the electro-magnets 54 which are mounted on a bracket 55 which is an extension of the horizontal member 49. The energization 10 of the magnets 54 attracts the head 56 of a T-shaped armature 57 which is supported by means generally designated 58 in connection with the magnets and the result of this is that the lower end of the standard portion of the armature engages the offset part of an arm 59 which is pivoted as indicated by the numeral 60 on a horizontal portion 61 of the bracket 55, so as to swing the depending cam portion 62 in a right hand direction. The arm 62 is slidably engaged with a pin 63 on the left hand end of the slide 64 which is mounted in projections 65, 66 on the member 49 so as to press the slide 64 in a right hand direction. The inner side of the slide 64 has a block 67 thereon which directly engages the adjacent end of the slug 7 as the slug falls upon the member 49 and the member 51 and pushes the slug to the right as shown in Figure 3, to the position occupied by the slug E in Figure 3 of the drawings. The immediately following slug coming into the position formerly occupied by the slug E is then operated upon by the head 67, so that in the end the desired number of selected slugs are positioned in the frame or holder 45 and the sign thereby composed. A spring 68 stretched between the head 67 and the projection 65 retracts the slide 64 and repositions the arm 62 and the armature 57 when the circuit is broken by release of the tiltable member 51. A stop pin 69 is arranged on the slide 64 to engage the projection 65 to limit outward retraction of the slide 64.

Referring now to Figure 4 of the drawings, there is therein shown a frame 45a which comprises a stand 70 suitable for resting on a counter or in a display case or other place on which is disposed the frame 45a which is in the form of a frame composed of upper and lower members 46a and 47a constructed as the members 46 and 47 in Figure 3 of the drawings joined at one end by the connector 71 and at the opposite end by the removable connector 72 which is removably held in place by a peg 73 engaging an opening in one end of the member 72 and a removable peg 74 in the member 46a for engaging an opening in the upper end of the member 72, whereby to retain the selected slugs 7 in the frame thus defined.

Referring now to Figure 5 there is therein shown a frame 45b which is similar in all respect to the frame 45a except that two rows of slugs are provided for by the interpositioning of the divider 75.

Referring now to Figure 6, wherein is shown an endless belt type of frame support, this comprises upper and lower rollers 76 and 77 over which are trained endless belts 78 and 79 and a sprocket chain 80 over sprocket formations at the adjacent ends of the rollers, one of the rollers being provided with an operating crank 81. Any suitable supporting means for the rollers (not shown) is provided so that the device will be in the nature of a bulletin board, upper slotted rails 46c, lower slotted rails 47c and intermediate

rails 75c being provided on the belts for quick alignment with the receiver mechanism, so that signs may be made up quickly on the wrong side of the exhibitor 45c and the crank 81 turned not only in placing the pairs of rails for reception of the slugs 7 but also for exhibiting the resultant signs as in a show-window or other place where the same is to be viewed.

Although I have shown and described herein preferred embodiments of my invention, it is to be definitely understood that I do not desire to limit the application of the invention thereto, and any change or changes may be made in the structure and arrangement of the parts, within the spirit of the invention and the scope of the subjoined claims.

Having described the invention, what is claimed as new is:

1. A sign composing device comprising a magazine involving guides, tiers of lettered slugs slidably supported by the guides, movable stop means engaging the lowermost slug, key means operatively connected to said stop means for releasing the lowermost slug, a chute in receiving relation to the released slug, a receiver in receiving relation to the chute, said receiver comprising a frame consisting of spaced rails, said frame being supported at one side of the lower end of said receiver, reciprocable means on said receiver for engaging and moving a slug dropped through said receiver to a position between said rails, and means to yieldably hold the slug just moved from leaving the position until pushed by similar moving of a succeeding slug.

2. A sign composing device comprising a magazine involving guides, tiers of lettered slugs slidably supported by the guides, movable stop means engaging the lowermost slug, key means operatively connected to said stop means for releasing the lowermost slug, a chute in receiving relation to the released slug, a receiver in receiving relation to the chute, said receiver comprising a frame consisting of spaced rails, said frame being supported at one side of the lower end of said receiver, reciprocable means on said receiver for engaging and moving a slug dropped through said receiver to a position between said rails, said reciprocable means comprising a slide having a head engageable with the dropped slug, normally open switch means which the slug operates as the slug falls to position to enter said frame, electrical means conditioned for operation by the closing of said switch means, said electrical means being operatively connected to said slide, whereby the slug is pushed into position between said rails as said electrical means is operated.

3. In a sign composing device, a receiver for receiving slugs, a frame consisting of spaced rails, said frame being supported at one side of the lower end of said receiver, reciprocable means on said receiver for engaging and moving a slug dropped through said receiver to a position between said rails, said frame comprising the mentioned spaced rails, a stationary connector between the outer ends of the rails, and a removable connector between the opposite ends of the rails for holding the slugs in place, said frame further comprising endless belt means on which the spaced rails are mounted, means supporting said endless belts for shifting the rails by moving the belts.

QUINTON BURAS.
